UNITED STATES PATENT OFFICE.

EUGENE L. DEACON, OF DENVER, COLORADO.

DESIGN FOR A SOUVENIR-SPOON.

SPECIFICATION forming part of Design No. 36,115, dated October 21, 1902.

Application filed April 28, 1902. Serial No. 105,123. Term of patent 7 years.

To all whom it may concern:

Be it known that I, EUGENE L. DEACON, a citizen of the United States of America, residing at Denver, in the county of Arapahoe and

5 State of Colorado, have invented a certain new, original, and ornamental Design for a Souvenir-Spoon; and I do declare the following to be a full, clear, and exact description of the invention, such as will enable others 10 skilled in the art to which it appertains to make and use the same, reference being had to the accompanying drawings, and to the figures of reference marked thereon, which form a part of this specification.

15 My invention relates to a new and original design for a souvenir-spoon; and it consists of the features hereinafter described and claimed, all of which will be fully understood by reference to the accompanying drawings, 20 in which is illustrated an embodiment thereof.

In the drawings, Figure 1 is a front view of a spoon, showing my new design. Fig. 2 is a side elevation or edge view of the same.

As shown in the drawings, the leading or 25 material feature of my design consists of a spoon having a handle whose upper extremity is bent rearwardly to indicate a ledge on the mountain side, upon which ledge is located

a miniature windlass or hoisting apparatus 8, the handle being slotted in front, as shown at 30 5^a, to show a miniature ore-bucket and cable, (designated 6 and 7, respectively.) In front of the windlass is shown a pile of rocks, while in the rear of the same appear tops of the mountains. Below the ledge on which the 35 windlass is located a tree appears. Upon the ledge and to one side of the windlass is a cabin. The sun appears beyond the mountains.

The face of the spoon-bowl is ornamented 40 to represent the bottom of a mining-shaft in which several persons appear at work. One man is using a shovel, another a drill, while two others are pushing an ore-car.

Having thus described my invention, what 45 I claim, and desire to secure by Letters Patent, is—

The ornamental design for a souvenir-spoon as herein shown and described.

In testimony whereof I affix my signature 50 in presence of two witnesses.

EUGENE L. DEACON.
